FIG. 1

UNITED STATES PATENT OFFICE

2,682,772

SAMPLING DEVICE

Herbert T. Peterson, Longview, Wash., assignor
to Weyerhaeuser Timber Company, Longview,
Wash., a corporation of Washington

Application February 16, 1953, Serial No. 337,201

9 Claims. (Cl. 73—424)

1

This invention relates to sampling devices, and provides an improved rotating screw sampling device for obtaining a continuous sample of both the liquid and solid phases of high-consistency pulps from vessels in which such pulps are contained under substantial superatmospheric pressure.

Many manufacturing processes, particularly those of a chemical nature, require close and substantially continuous control of operating conditions. In such processes it is often necessary to obtain frequent or continuous samples of the material being processed for purposes of analysis and control. For example, in the manufacture of cellulose from wood pulp, it is desirable to make frequent or continuous pH or other determinations on the liquid component of cellulosic pulps undergoing treatment, and it is also desired sometimes to make tests on the pulp fibers. It is difficult, however, to provide for continuous or frequent withdrawal of small test samples of such pulps, especially when they are of high consistency and are being processed at high pressures.

I have devised an improved sampling device for continuously withdrawing a small sample of the liquid component of high consistency pulps, which sample also contains a small proportion of the solid component of the pulp. The new sampling device comprises a rotating screw element mounted for rotation within a sampling tube having an inlet opening at its outer end and a discharge opening at its inner end. The rotating screw element comprises a shaft which is provided with inner and outer helical screw flights of opposite pitch. The outer helical screw flight is disposed on the shaft adjacent the inlet opening of the sampling tube, and the inner helical screw flight is disposed on the shaft adjoining the outer screw flight and extending along the shaft toward the discharge opening of the tube. Means are provided for rotating the shaft in the direction which causes the outer helical screw flight to appear to travel outwardly, whereby excessive accumulation of solid material at the inlet opening of the sampling tube is prevented. Simultaneously the inner helical screw flight appears to travel toward the discharge opening of the tube, and thereby it propels toward such discharge opening the small sample of stock liquor and pulp fibers which work their way past the outer screw flight.

The rotatable shaft of the rotating screw element advantageously is mounted for reciprocating movement along its longitudinal axis and is

2

provided with means for moving it back and forth within the sampling tube. The reciprocating motion thus imparted to the shaft and screw flights is effective for keeping the inlet opening of the sampling tube free from solid material, which otherwise would accumulate there and clog the tube, even when the pulp is of very high consistency and is being processed at high pressure.

10 A particularly advantageous embodiment of the new sampling device is described below in connection with the accompanying drawings, in which:

Fig. 1 is a longitudinal section through the new sampling device;

Fig. 2 is a top view of one end of the device showing the reciprocating mechanism at one limit of its travel, and

Fig. 3 is a cross section taken substantially 20 along the line 3—3 of Fig. 2.

The sampling device comprises a sampling tube 10 having an inlet opening 11 at its outer end and a discharge opening 12 at its inner end. A shaft 13 is mounted for rotation about and for reciprocating movement along its longitudinal axis within the sampling tube 10. The shaft 13 is provided with outer and inner helical screw flights 14 and 15, respectively, of opposite pitch; that is, one of the helical screw flights 15 corresponds to a right-hand screw thread and the other flight 14 corresponds to a left-hand screw thread. The outer helical screw 14 is disposed on the shaft 13 adjacent the inlet opening 11, and projects slightly therebeyond. The pitch of the screw flight is advantageously not very steep, and it comprises rather few complete turns. The inner helical screw flight 15 extends along the shaft 13 from the inner end of the outer flight about to the discharge opening 12 of the sampling tube 10. The pitch of this inner screw flight is advantageously somewhat steeper than that of the outer flight, and of course it comprises a sufficient number of turns to extend from where it adjoins the outer flight to the discharge opening of the tube 10.

40 The discharge opening 12 of the sampling tube 10 communicates with a sample collection chamber 16. This chamber is provided with a nipple 17 through which liquid delivered into the chamber 16 through the tube 10 may be withdrawn. A tapped access opening 18, into which a vent pipe or other device may be threaded, is provided in the upper portion of the collection chamber 16. A bearing support 19 is attached to 50 the wall of the collection chamber opposite the

sampling tube 10, and a bearing 20 is mounted therein. The bearing support 19 may advantageously be provided with a lubrication fitting 21, and, if desired, with a packing and packing nut 22.

The shaft 13 extends inwardly through the discharge opening 12, across the collection chamber 16, and through the bearing 20, and is rotated by a motor 25. The motor is connected to the shaft by means of a coupling collar 26, a coupling flange 27 and coupling pins 28. The coupling collar 26 is secured to the end of the shaft 13 by a set screw 29, and the coupling flange 27 is secured to the motor shaft by a set screw 30. The coupling pins 28 are rigidly fixed to the coupling collar 26 and extend through holes in the coupling flange 27. The motor 25 rotates in the direction which causes the inner helical screw flight to appear to travel inwardly toward the discharge opening 12 and which causes the outer helical screw flight 14 to appear to travel outwardly toward the inlet opening 11 of the sampling tube 10. This is the direction of rotation which causes the inner flight 15 to cause material to move through the sampling tube 10 toward the discharge opening 12 thereof.

In addition to means for rotating the shaft, a mechanism is provided to cause the shaft 13 to reciprocate back and forth along its longitudinal axis. The reciprocating mechanism shown comprises a peripheral cam groove 33 formed in the outer surface of the coupling collar 26, a fixed collar 34 surrounding the coupling collar, and a cam follower 35 held by the fixed collar and riding in the cam groove 33. The cam groove 33 extends completely around the coupling collar 26, and follows an elliptical path lying in a plane disposed at an angle other than perpendicular to the longitudinal axis of the shaft 13. The fixed collar 34 is secured to support brackets 36 which maintain it in a fixed position. The cam follower 35 advantageously is a hard steel ball received in a hole drilled in the fixed collar and held in place by a set screw 37. As the coupling collar 26 is rotated by the motor 25, the cam follower 35, traveling in the elliptical cam groove 33, causes the coupling collar to move back and forth. The reciprocating motion thus imparted to the coupling collar 26 causes the shaft 13 and its associated helical screws to move back and forth within the sampling tube as the shaft rotates. The coupling collar and the shaft are shown in Fig. 1 to be at the innermost limit of travel of their back and forth movement, while Fig. 2 shows the coupling collar and shaft, having been rotated one-half revolution, at the outermost limit of their travel.

To use the sampling device, the outer end 11 of the sampling tube 10 is inserted into the slurry or pulp to be sampled. When the device is inserted through an opening in the wall of the vessel containing such slurry or pulp, an adapter plug 38 and packing nut 39 may be provided to make a leak-tight joint between the wall of the vessel and the outside of the sampling tube. As the motor 25 rotates the shaft 13, the outer screw flight 14 holds the bulk of the solid material away from the inlet opening 11 of the sampling tube. Some of the liquid component of the pulp, however, finds its way past the threads of the outer screw flight 14 and reaches the inner helical screw 15. Thereupon the inward travel of the threads of the inner screw 15 conveys it rapidly to the collection chamber 16. The sample thus collected generally contains a small quantity of the

solid component of the pulp, but it is free from the bulk of such solid material. It does, however, contain enough of the solids to permit performing control or other tests thereon.

5 The combination of outward travel of the threads of the outer helical screw flight 14, and the back and forth motion of the shaft and helical screw flights carried thereby, prevents the accumulation of an excess of solid material about 10 the inlet opening 11 of the sampling tube 10, and thereby prevents clogging of the tube with such accumulation. The over-all length of the outer screw flight 14 should be at least equal to and 15 preferably somewhat greater than the stroke of the shaft 13, so that the reciprocating movement of the latter does not at any time bring the inner screw flight 15 to beyond the inlet opening 11.

Sampling devices constructed in accordance with my invention have been successfully used 20 to obtain continuously samples of the sulfite stock liquor from high density cellulosic pulps. One such sampling device used for this purpose was provided with inner and outer helical screw flights of opposite pitch, as described above, but 25 had no provision for reciprocating movement of the screw flights along the longitudinal axis of the sampling tube. This sampling device has been used successfully to obtain samples of sulfite liquor from pulps having a consistency up to 6% 30 by weight of cellulosic fibers. Another sampling device according to my invention, constructed as described above with mechanism for reciprocating the shaft along its longitudinal axis, has been used successfully to obtain samples of the stock 35 liquor from pulps containing up to 16% of cellulosic fibers and maintained at pressures in excess of 100 pounds per square inch. With pulp mixtures of the latter consistency, there has been heretofore no satisfactory way to obtain samples 40 of the liquor more or less continuously for pH control of the pulp. With my sampling device, however, such samples may readily be obtained, and without interruption due to clogging of the sample tube with an accumulation of pulp or 45 other solid material.

I claim:

1. A sampling device of the character described comprising a sampling tube adapted to be mounted with one end extending into the material 50 to be sampled, a shaft extending through said tube and mounted for rotation therein, a first helical screw flight disposed on said shaft adjacent the inlet end of the sampling tube, a second helical screw flight of opposite pitch to said first flight disposed on the shaft adjoining said first flight and extending along the shaft toward the discharge end of said tube, and means for rotating said shaft in the direction to cause said first screw flight to urge material outwardly away from 55 the inlet opening of the sampling tube and said second screw flight to convey material to the discharge opening of said tube.

2. A sampling device of the character described comprising a sampling tube adapted to be 60 mounted with one end extending into the material to be sampled, a shaft extending axially through said tube, said shaft being mounted for rotation about and for linear movement along its longitudinal axis, a first helical screw flight disposed 65 on said shaft adjacent the inlet end of the sampling tube, a second helical screw flight of opposite pitch to said first flight disposed on the shaft adjoining said first flight and extending therefrom toward the discharge end of said tube, means 70 for rotating the shaft and screw flights thereon, 75

and reciprocating means for moving the shaft back and forth along its longitudinal axis.

3. A sampling device of the character described comprising a sampling tube adapted to be mounted with one end extending into the material to be sampled, a shaft mounted for rotation within said tube, said shaft carrying inner and outer helical screw flights of opposite pitch, the outer helical screw flight being disposed on the shaft within the sampling tube adjacent the sample inlet end thereof and the inner helical screw flight being disposed on the shaft adjoining said outer flight and extending along said shaft toward the sample discharge end of said tube, and means for rotating the shaft in the direction to cause said inner screw flight to move material toward the sample discharge end of said tube.

4. A sampling device of the character described comprising a sampling tube adapted to be mounted with one end extending into the material to be sampled, a shaft extending through said tube and projecting slightly beyond the sample inlet end thereof, said shaft carrying inner and outer helical screw flights of opposite pitch, the outer helical screw flight being disposed on said shaft adjacent the inlet end of the sampling tube and extending from within the tube to slightly beyond said end, and the inner helical screw flight being disposed on the shaft adjoining said outer screw flight and extending along said shaft toward the sample discharge end of said tube, and means for rotating the shaft in the direction to cause said inner helical screw flight to move material toward the sample discharge end of said tube.

5. A sampling device in accordance with claim 4 in which the pitch of the outer helical screw flight is less steep than the pitch of the inner helical screw flight.

6. A sampling device of the character described comprising a sampling tube adapted to be mounted with one end extending into the material to be sampled, a shaft mounted axially within the sampling tube for rotation about and for reciprocating movement along its longitudinal axis, said shaft carrying inner and outer helical screw flights of opposite pitch, said outer helical screw flight being disposed on the shaft adjacent the sample inlet end of the sampling tube and said inner helical screw flight being disposed on the shaft adjoining said outer screw flight and extending toward the sample discharge end of said tube, means for rotating the shaft in the direction to cause said inner helical screw flight to move material toward the sample discharge end of said tube, and means for simultaneously reciprocating the shaft back and forth along its longitudinal axis.

7. A sampling device of the character described

comprising a sampling tube adapted to be mounted with one end extending into the material to be sampled, a shaft mounted axially within the sampling tube and projecting slightly beyond the sample inlet end thereof, said shaft carrying inner and outer helical screw flights of opposite pitch, said outer helical screw flight being disposed on the shaft adjacent the sample inlet end thereof and projecting slightly beyond said end and said inner helical screw flight being disposed on the shaft adjoining said outer screw flight and extending toward the sample discharge end of said tube, means for rotating the shaft in the direction to cause said inner helical screw flight to move material toward the sample discharge end of said tube, and means for simultaneously reciprocating the shaft back and forth along its longitudinal axis.

8. A sampling device according to claim 7, in which the length of the outer helical screw flight is greater than the length of the stroke of the reciprocating shaft, whereby reciprocation of the shaft does not at any time cause the inner screw flight to pass beyond the sample inlet end of the tube.

9. A sampling device of the character described comprising a sampling tube adapted to be mounted with one end extending into the material to be sampled, a shaft mounted for rotation and for reciprocating movement within said tube, said shaft being provided with an outer helical screw flight disposed on the shaft adjacent the inlet end of the sampling tube and with an inner helical screw flight of opposite pitch to said outer screw flight disposed on the shaft adjoining said outer flight and extending toward the inner end of the sampling tube, a coupling collar secured to said shaft and provided with a peripheral cam groove extending completely therearound, the path of said cam groove lying in a plane disposed at an angle other than perpendicular to the longitudinal axis of the shaft, a fixed collar surrounding said coupling collar and provided with a cam follower protruding from its inner surface into said cam groove, and means for rotating the shaft in the direction to cause the inner helical screw flight to move material toward the discharge end of the sampling tube, whereby said shaft is simultaneously caused to move back and forth along its longitudinal axis.
